UNITED STATES PATENT OFFICE

2,490,575

PUMP

Benedetto Bartolucci, Chicago, Ill.

Application June 15, 1946; Serial No. 676,920

2 Claims. (Cl. 103—114)

1

The present invention relates generally to pumps, but more particularly to a novel, simplified and efficient type of industrial pump adapted to be used in connection with supplying liquid under pressure for various machine shop uses or the like for drilling machines, automatic machines, milling or other similar machines where the liquid is used for cooling purposes in the operation of tools and the like.

One of the objects of the present invention is to provide a very efficient and simplified construction of an industrial pump which can be easily and quickly dismantled for the purpose of inserting liners and to permit easy access to the operating parts of the pump.

A further object of the invention is to provide a simple and more efficient pump in which the main shaft of the pump is supported on one side thereof and thereby prevents the necessity of removing the bearings so that access to the pump housing may be had without dismantling the pump shaft.

These and other objects are accomplished by providing a construction and an arrangement of the various parts in the manner hereinafter described and particularly pointed out in the appended claims.

Referring to the drawings:

Fig. 1 is a side elevational view of my improved pump construction;

Fig. 2 is an enlarged longitudinal cross sectional view in which the parts are diagrammatically displaced for the purposes of showing the manner in which the pump housing is disassembled to permit the removing and replacing the liners thereof;

Fig. 3 is a similar cross sectional view showing the pump in assembled form; and

Fig. 4 is a fragmentary cross sectional view taken on the lines 4—4 in Fig. 3 of the drawings.

In illustrating one form of my invention, I have shown the same as comprising a main horizontal base member 10 on which is secured a substantially U-shaped bearing support 11. Mounted on and secured to the upper surface of the arms of the bearing support 11 are two spaced apart pillow block bearings 12. Journaled in suitable anti-friction bearings 13 in each of the pillow blocks 12 is a main pump shaft 14. Mounted on the main base 10 on one side of the support 11 in the manner well understood in the art, is an electric motor, generally indicated by the reference character 15. The electric motor 15 is provided with the usual drive shaft 16 and has one end thereof connected to the pump shaft

2

14 by a coupling 17. Located on the other side of the bearing support is a pump housing generally indicated by the reference character 18. The pump housing in this case comprises a removable dome-like section 19 and a somewhat similar stationary section 20. The housing section 20 has a horizontal flange portion 21 for the purpose of securing this section to the main base 10 by means of bolts 22. The housing section 20 is provided with a sleeve-like hub 23 through which the pump shaft 14 extends. Surrounding the shaft 14 within the sleeve is the usual packing 24. Between certain parts of the packing is a packing lubricating ring 25. The packing rings are held in position by the usual adjustable packing gland 26. Secured to the outer end of the shaft 14 is a rotor in the form of two radially projecting blades 27, which have their inner ends conforming to the surface of the shaft and clamped thereto by bolts 27'. Mounted within and complementary to each of the housing sections 19 and 20 are replaceable liners or inner pump casting members 28 and 29 respectively. The outer surface of the inner liner member 29 is provided with concentrically arranged annular finished flanges 31 and 32 which are adapted to contact concentrically arranged annular flanges 33 and 34 respectively of the housing section 20 so as to impinge therebetween the respective gaskets 35 and 36. In a similar manner, the inner liner member 28 is provided with concentrically arranged annular flanges 37 and 38 which are complementary to the annular flanges 39 and 40 of the housing section 19 respectively, so as to impinge therebetween the respective gaskets 41 and 42. The inner liner member 28 has a relatively large central opening 43 which is in alignment with a central bore 44 in the housing section 19. Formed integrally with the housing section 19 is an elbow shaped connection 45 which terminates in a connecting flange 46. This elbow 45 and connection 46 forms the inlet to the axial center of the pump. The inner liner member 29 has a vertically extending conduit or tubular portion formed integrally therewith as shown at 47 which is arranged tangentially to the periphery of the member 29 and forms the outlet port as shown at 48 through which the liquid is discharged by the rotor or pump member 27. The outer surface of this discharge conduit or tubular extension 47 has complementary and embracing portions formed on the housing sections 19 and 20 as shown respectively at 49 and 50 so as to embrace the same when the complementary housing sections 19 and

20 are bolted together. Formed integrally with the respective housing members **19** and **20** are horizontal connecting flanges **51** and **52** for connecting suitable conduits to the discharge or outlet of the pump proper. A suitable gasket **53** is provided for the circular flanges **51** and **52** for connecting the same to a suitable conduit. The inner liner members **28** and **29** have complementary convex recesses **54** and **55** which conform substantially to the configuration of the revolving rotor or pump member **27**. The liner member **28** has its inner face formed in the annular finished surface as shown at **56** which is adapted to seat on a complementary finished surface **57** on the inner liner **29** to completely encase the rotor. The housing members **19** and **20** are provided with peripheral complementary flanges **59** which are secured together by uniformly spaced apart bolts **58**.

From the above description it will be obvious that should it be desirable to replace the inner liner members **28** and **29**, which occasionally become worn, by reason of wear through the action of abrasive materials or metal shavings circulated with the liquid through the pump, all that is necessary for the operator to do is to remove the bolts **58** from the adjacent flanges **59** of each of the housing members **19** and **20**, disconnect the coupling member **17** and remove the outer housing section **19** and inner liner members **28** and **29** and the main shaft **14** with the rotor **27** in the manner diagrammatically illustrated in Fig. 2 of the drawings. This arrangement permits easy access to the operating parts and liners of the pump. It will also be obvious that by supporting the main shaft **14** in the bearings on one side of the pump housing that considerably less effort and time is required to replace the inner liners that would ordinarily be required if the bearings had to be removed. It will also be noted that by positioning the electric motor on the other side of the bearings the whole pump structure affords a balanced power driven pump of great efficiency.

While in the above specification I have described one embodiment which my invention may assume in practice, it will, of course, be understood that modification may be made therefrom without departing from the spirit and scope of the invention as expressed in the appended claims.

What I claim as my invention and desire to secure by Letters Patent is:

1. A pump comprising a housing in the form of a relatively stationary housing section and a removable section, an inner liner casing in the form of complementary liner sections, two concentrically arranged annular finished surfaces on the outside surfaces of said liner sections complementary to corresponding finished annular surfaces on each of said housing sections, the two concentrically arranged surfaces on each side of the liner sections being located in the same vertical plane gaskets impinged between said annular surfaces, a shaft journaled in said stationary housing section, and a rotor secured to said shaft and rotatable in said inner liner casing.
- 15 2. A pump comprising a base member, a bearing secured to said base, a pump shaft journaled in said bearing, a pump housing comprising two complementary dome-like sections, one of said sections secured to said base, the other section 20 removably secured to said first named section, an interliner casing in the form of complementary liner sections, one of said liner sections having a discharge conduit positioned tangentially with respect thereto, two concentrically arranged annular finished surfaces on the outside 25 surface of each of said liner sections complementary to corresponding finished surfaces on each of the housing sections, the two concentrically arranged surfaces on each side of the liner sections being located in the same vertical plane said pump housing having a liquid inlet thereto and a liquid discharge outlet located tangent to the periphery of said inner casing, a rotor 30 secured to said shaft within said inner casing, 35 peripheral flanges formed on said housing sections, and bolts extending through said flanges for securing said sections together whereby one housing section may be removed for replacing inner casing sections without disturbing said bearing.

BENEDETTO BARTOLUCCI.
